UNITED STATES PATENT OFFICE.

FRED M. OPITZ, OF RACINE, WISCONSIN.

RADIATOR-CORE.

1,381,655.

Specification of Letters Patent. Patented June 14, 1921.

Application filed November 10, 1919. Serial No. 336,934.

To all whom it may concern:

Be it known that I, FRED M. OPITZ, a citizen of the United States, residing at Racine, in the county of Racine and State 5 of Wisconsin, have invented a certain new and useful Improvement in Radiator-Cores, of which the following is a full, clear, concise, and exact description, reference being had to the accompanying drawings, forming 10 a part of this specification.

My invention relates to radiator cores and to the method of making the same, the radiator being of that type which employs a series of hollow tubes which are arranged 15 preferably in parallel relation between two water chambers, the one for the incoming warm water, and the other for the outgoing cool water.

While the active elements are in the form 20 of tubes I form the front or face of the core with a cellular formation giving it the appearance of a cellular radiator. I have given this type of radiator the name of "cellutubular."

25 A principal object of my invention is to provide such a radiator wherein the water conducting sections may be constructed of very thin sheet metal, presenting a maximum cooling surface to the air-currents 30 passing and which sections when assembled into a radiator make a strong, sturdy structure, employing a minimum of metal in its construction, and which may be economically manufactured and which will give a 35 minimum of trouble in service.

It has been found in practice that considerable difficulty has been experienced with the radiators of the prior art when used in very cold weather since, if the water 40 freezes, the containing tubular sections are not sufficiently flexible to take up the expansion of volume due to the conversion of the water from a fluid to the solid form of ice, and therefore, these tubes have been 45 caused to rupture and the radiators have been subsequently caused to leak; it is another object of my invention, therefore, to provide a tubular core having sufficient elasticity in its walls, so that the danger of 50 rupture due to the freezing of the contained water will be practically eliminated.

It is a further object of my invention to provide an improved sheet metal radiator core, having corrugated water conducting 55 tubes which are of such formation as to present an extensive cooling surface rela-

tive to the amount of contained water, and in order to accomplish this I provide flattened tubes which are constructed by fastening together two identically formed complementary sheet metal sections, face to face, the edges being sealed together, the said sections preferably having longitudinal crimps or corrugations. The flattened tube is mounted in a supporting structure 60 consisting of corrugated fin units constructed of sheet metal which units are horizontally folded to make cellularly formed corrugations. The corrugated units are longitudinally creased or impressed on one side 65 to form a trough-like surface on one of the corrugated sides of the fin unit, which trough-like surface is adapted to engage and support the coöperating outside wall of the above mentioned flattened tube section. 70

Another object of my invention is to provide a process of manufacture for the making of my improved radiator cores, by virtue of which the said cores are produced using a minimum of metal, and in which 80 the core walls are of substantially the same thickness as the original metal sheet, and possess the above mentioned and other advantages which will later be made apparent from the description of my invention which 85 follows, and in which description reference will be made to the following figures in which like reference characters will be used to designate like parts. Referring now to the figures:

Figure 1 shows a plan view of a radiator core embodying my invention;

Fig. 2 shows a front elevation of the radiator core illustrated in Fig. 1;

Fig. 3 shows an isometric view of one of 95 the sheet metal units, two of which when placed together form a radiator water tube or channel;

Fig. 4 shows an isometric view of a fin unit, two of which are required to hold the 100 radiator tube section, and which are adapted to form air-flues for the passage of air-currents through the radiator;

Fig. 5 is a horizontal section of the radiator core assembly of Fig. 2 taken on the 105 line 5—5 of Fig. 2;

Fig. 6 is a horizontal sectional view of the radiator core assembly illustrated in Fig. 2 taken on the line 6—6 of Fig. 2;

Fig. 7 is a vertical cross-sectional view of 110 the radiator core assembly, taken on the line 7—7 of Fig. 1;

Fig. 8 shows a plan view of a pair of tube units or halves and a pair of fin units, which are adapted to form a core section, the two tube units being adapted to be brought together to form a water containing tube and the fin units being adapted to be brought together to securely clamp the intervening tube in place, the several parts illustrated in this figure being shown slightly separated 10 in order to illustrate the assembly of the several parts; and

Fig. 9 is a front elevation of a filler or spacing unit.

According to my invention I form the 15 vertical water tubes of complementary gutter members having flat joining flanges. Between and in contact with these gutter members I provide spacing strips which perform the usual function of mechanically supporting and protecting the thin tubes and of radiating and conducting heat from the tubes.

These filler or spacing strips extend both 25 front and back beyond the edges of the tubes. These strips are folded back and forth to form a regular pattern such as a hexagonal figure or a half of the same, so that when these strips are placed in contact they form at front and rear a cellular structure. Preferably these strips are formed 30 into unitary sections by placing two such strips back to back and joining the strips at top and bottom.

Each strip is channeled at its central part 35 to receive or embed half of the water tube. The result of this construction is that the front edges of the spacers or filler strips are all in contact and completely hide the front edges of the tubes where the spacers 40 or fillers are in contact. The tubes of course extend across the cellular openings which are formed by the fillers or spacing strips. The ends of the tubes are cut off flush with the tops of the spacers and consequently no 45 further operation is required to finish the radiator core for the water headers. The finished core comprises a series of cellular openings running transversely from front to back of the core forming air channels the 50 air channels being bounded by the filler strips which serve at the same time as radiating fins. The water tubes run vertically through the air channels and are hidden behind the fronts of the radiating fins.

The tubes are made of identical halves 55 and the filler or radiating sections on each side of the tube are identical, being merely reversed. As a consequence my radiator core may be made up of two parts only, appearing in multiple, namely the filler strip assembled in pairs to make a filler or spacing unit and the gutter strip, two of which are assembled as complementary halves to form a tube.

Referring to the drawings, and in par-

ticular to Fig. 4 wherein I show a view of a fin unit of which two are adapted to clamp between them a water containing tube section securely in place; this fin unit is formed of a single piece of thin sheet metal, the sheet 70 being transversely folded to provide a series of corrugations 8 and 9, the ridges of corrugations 8, located on one side of the unit, being grooved longitudinally of the unit, and transversely of the corrugations. 75

Each ridge 8, is thus grooved between the points 10 and 11, this longitudinal groove being deeper at portions 12 and 13 than at the intermediate ridge 14, provided at an intermediate portion and at steps 15 and 16, 80 which are formed at the outer edges of the groove. A cross-sectional view giving the configuration of the longitudinal grooves is shown in Fig. 8 for each of the fin units A and B.

The sheet of metal folded as above described and comprising the fin unit A, has an offset end *a* and a straight end *b*, the end *a* of fin unit being adapted to nest or mesh with an end *b* of an adjacent unit as illustrated in Figs. 2 and 7. The finished filler strips while similar, are alternately reversed, end for end.

The filler strips as illustrated are formed of a continuous strip of sheet metal which 95 is preferably stamped progressively in a stamping machine, which machine after forming a predetermined length of such strip cuts off a unitary length. The ends are then flanged as at *a* and the fin or filler sections are finished ready to assemble in pairs back to back as illustrated in Fig. 9 to form fin or filler units D.

The water tubes or channels are also formed of strips of sheet metal which are 105 preferably rolled by a pair of rolls into the channel or gutter shape illustrated in Figs. 3 and 8 and then cut into suitable lengths. These gutters or channels may be formed by stamping suitable lengths of 110 strip if desired. The units or channels C have the joining margins or flanges 17 and an intermediate ridge or crease 20. The portions 18 and 19 lying on opposite sides of the central ridge 20 provide water passageways.

As shown in Figs. 1, 5, 6 and 8 the vertical tubes are formed of two halves C facing each other and joined along the joining margins 17.

To assemble the above described units into a core the two channel or gutter members C are placed face to face and complementary fin or filler sections D are laid on each side as illustrated in Fig. 8. The channel or gutter sections C fit into the sides of the adjacent fin or filler sections D being embedded therein as will be apparent from the drawings. The central projections 14 on the filler strips A fit into the groove or 125 130

crease 20 of the channel or gutter members C to center these gutters with respect to the fins or filler strips.

It will be noted that the offset portions 15 5 are quite shallow. These offsets are of a depth corresponding to the thickness of the metal of the gutter members so that when the gutter section is laid into the side of the fin or filler section the joining margins 10 17 lie flush with the adjacent sides of the corrugations 8.

The water containing tubes are sealed at their sides where the flanges 17 are brought into contact, by dipping the edges of an assembly of radiator core sections such as that illustrated in Figs. 1, 2, 5, 6 and 7, into melted solder, portions of the assembly which are immersed being the joined edges 25 of the corrugations 8, of the fin units and 20 the joined faces of the flange 17 of the tube units C, together with the clamping steps 15 of the inclosed fins, the two edges of the core assembly being alternately dipped into the melted solder to seal all of the end 25 flanges of the fin and tube units securely together. A plurality of core sections such as the sections D, E, and F being assembled together, with the adjoining portions of their fin extensions 9, soldered together, the 30 lapped ends a and b of the adjoining units are joined as illustrated in Figs. 2 and 7, these lapped ends likewise being soldered together forming a unitary assembly of cellular supporting air-flues G, carrying integrally formed water tubes and which tubes 35 are left open at their top and bottom ends to provide at the top of the assembly, as illustrated in Fig. 1, openings for incoming warm water to flow into the tubes 21 and 22, and 40 likewise providing similar openings at the bottom for the egress of the air-cooled water.

It will be observed that the core is thus finished at the top and bottom so that a suitable water header or box can be attached directly to the top and bottom of the core along the front and rear edges without further operations or special fittings.

The dipping of the faces of the core in melted solder seals the edges of the tubes 50 front and back and unites the fins or filler units with the front of the tubes in a good mechanical and heat conducting joint. The tubes are not joined along the central ridge 55 as there is no necessity for the same. However, said central ridges effectively prevent the collapse of the tubes.

The core has very considerable elasticity and is peculiarly free from damage by strains such as generally occur in radiator 60 cores employed for trucks or tractors, to which use this core is particularly adapted.

It will be noted that the joint or seam between the fins at the faces 8 lies in the same plane as the joint or seam between the joining margins 17 of the tube. A very im-

portant function flows from this result, namely that a section may be taken out by melting the solder and pushing the section out like a drawer. This is possible because the two halves of the tube will slide over each other and further because the closure for the tubes with the water boxes is made at top and bottom by the fins as is clearly apparent from Figs. 1 and 2. This permits a radiator to be repaired if any part is damaged by withdrawing one or more sections and replacing them with new sections—a very desirable result.

Having thus described my invention as embodied in a specific structure, I am aware 80 that numerous and extensive departures may be made from the embodiment herein illustrated and described, without departing from the spirit of my invention, and such modifications are contemplated.

I claim:

1. In combination, a pair of gutter members having flat joining margins lying in contact to form a tube, a pair of filler strips corrugated into a regular pattern, the corrugations of each strip being indented to embed said gutter members, the front and back edges of the filler strips extending in front and back of the joining margins and lying in contact, said joining margins and 95 said extensions of the corrugations being joined by solder, the joints between the margins of the gutters and between the extensions of the corrugations lying in the same plane.

2. In combination, a pair of gutter members having flat joining margins, said gutter members having their joining faces lying in contact to form a tube, a corrugated facing strip lying on each side of the tube, the corrugations on said strip being reduced at the central part to embed the tube and the outer edges of the corrugations being unreduced whereby they are brought into contact in substantially the same plane 110 as adjoining faces on said gutter members, the unreduced edges of the corrugations and the joining faces of the gutter members being joined by solder.

3. In combination, a pair of corrugated strips bent back and forth to form halves of a closed pattern such as a hexagon, said strips being laid back to back with the bottoms of the corrugations in contact, the upper and lower ends of the strips being joined to form a face at substantially right angles to the length of the strips, the tops of the corrugations being reduced longitudinally along the central part of the strips to embed the parts of water tubes, said 120 water tubes having joining faces lying in the planes of the ends of the tops of the corrugations.

4. In combination, a pair of gutter members forming tube halves, a pair of corru-

gated strips, the corrugations of each strip being indented to receive and embed a gutter member, the edges of the corrugations extending beyond the lateral edges of the 5 gutter members, said corrugated strips being placed in contact side by side so that the corresponding tops of corrugations lie in contact and the edges of the gutter lie in contact in substantially the same plane, with 10 a filling of solder joining the edges of corrugations where they are in contact, and the edges of the gutters, to define water tubes, said corrugated sheets defining transverse air passages.

15 5. In a radiator, a series of tubes each comprising a pair of complementary gutters having flat joining margins substantially at the center of the front and rear of each tube, and filler strips defining air cells 20 and lying between adjacent tubes in contact

with the side walls of adjacent gutters, said filler strips being joined to each other on joining margins lying in the same planes as the joining margins of the gutters.

6. In a radiator, a series of tubes each 25 comprising a pair of complementary gutters having flat joining margins substantially at the center of the front and rear of each tube, and filler strips defining air cells and lying between adjacent tubes in contact with 30 the side walls of adjacent gutters, said filler strips being joined to each other on joining margins lying in the same planes as the joining margins of the gutters, said filler strips completely embedding the joining margins 35 of the contiguous gutters.

In witness whereof, I hereunto subscribe my name this 5 day of November, A. D. 1919.

FRED M. OPITZ.
